UNITED STATES PATENT OFFICE.

JOHN H. KERR, OF FORT MILLS, CORREGIDOR, PHILIPPINE ISLANDS.

COMBINED LINE-REEL AND MARKER OR CHALKER.

1,338,935.

Specification of Letters Patent.

Patented May 4, 1920.

Application filed April 28, 1919. Serial No. 293,260.

To all whom it may concern:

Be it known that I, JOHN H. KERR, a citizen of the United States, residing at Fort Mills, Corregidor, in the county of Cavite, Philippine Islands, have invented certain new and useful Improvements in Combined Line-Reels and Markers or Chalkers, of which the following is a specification.

My invention relates to a combined line reel and marker or chalker.

The principal object of my present invention is to provide a device of this general character which will effectively chalk a line which will be carried in a position where it will be in engagement with the chalk at all times.

A second object of the invention is to provide a combined reel and chalk holder which embodies a novel means for resiliently retaining the chalk in operative position.

A further object is to provide a chalking device of this general type which may be in the form of a shoe or other design which will be attractive as well as efficient in use.

The above general objects and others will be fully set forth in the following disclosure and explicitly defined in the appended claims.

The inventive idea embodies particular coöperating parts, arrangements and operations, which will be set forth in detail.

On the drawing:

Figure 1 is a side elevation of my improved line reel holder and chalk marker, the forward end thereof being shown in section, and

Fig. 2 is a top elevation of the same.

Referring to the drawing, the numeral 10 designates the body or holder, which in this instance is shown in the shape of a shoe, but any other ornamental design may be substituted therefor. This holder may be constructed from any suitable material such as lead or any other heavy material so that the device will not be easily displaced or knocked over. The rear end of the body is provided with a cupped recess 11, in which is positioned a spool or reel 12 keyed on a rotatable shaft 13. The shaft 13 is carried by the body and has mounted upon one end thereof a crank handle 14 by means of which the shaft is rotated for rotating the spool or reel.

Formed in the forward end of the body is a chalk receiving recess 15 which contains a block of chalk 16. Positioned at the upper

end of this recess and closing the same is a cover 17 which has a handle 18 secured thereto. Secured to the under face of the cover 17 at diametrically opposite points are resilient chalk engaging clips 19 which are bent, as at 20 to afford shoulders which engage in notches 20' in the side walls of the recess 15. The lower extremities of these resilient clips are extended upwardly and then laterally toward each other, which upwardly and laterally extending extremities engage with recesses formed in the sides of the chalk. These resilient clips force the block of chalk 16 downwardly toward the bottom of the recess 15.

A longitudinally extending passage 21 is formed in the body 10 communicating at its forward end with the outer end of the body and at its inner end with the recess 15. An enlarged bore 22 extends longitudinally of the body also and communicates at its forward end with recess 15 and at its rear end with recess 11.

A cord, or other flexible element 23 is wound upon the spool or reel 12 and is passed through the bore 22 into recess 15. Here it is passed under the block of chalk 16 and is then passed through passage 21 and led from the forward end of the body 10, as shown. The outer extremity of this flexible element 23 is provided with a button 24 which is adapted to be grasped to withdraw the flexible element from the body.

It will be manifest that when it is desired to withdraw the flexible element through the body to mark the same, the button 24 is grasped and pulled forwardly to withdraw it, and when it is desired to inclose this flexible element within the body, the handle 14 is rotated to wind this element therearound.

While this disclosure embodies the preferred embodiment of the invention, it is to be understood that the same is susceptible to various alterations and modifications that may be embodied in the appended claims.

What is claimed is:

1. In combination with a body having a recess therein and passages leading from each side of the recess and through which and the recess a flexible element may pass, of a block of chalk carried within the recess to engage the flexible element, a closure for closing the outer end of the recess and resilient means connected to the closure for releasably holding the same in a closed position and at the same time engage the block

of chalk for forcing the same away from the closure as and for the purposes set forth.

- 5 2. In combination with a body having a recess therein and passages leading from opposite sides of the recess and through which and the recess a flexible element may pass, of a block of chalk positioned within the recess, said body also having notches communicating with the recess, a cover for the recess having resilient chalk engaging clips fixed thereon of substantially V-form where-
- 10

by the clips will engage within said notches to releasably hold said cover in a closed position and at the same time will bear upon 15 said block of chalk for forcing the same away from the cover, as and for the purposes set forth.

In testimony whereof I affix my signature in presence of two witnesses.

JOHN H. KERR.
